UNITED STATES PATENT OFFICE.

GEORGE HENRY DOWNS, OF NORTH POWDER, OREGON, ASSIGNOR OF ONE-HALF TO WILLIAM E. GRACE, OF BAKER CITY, OREGON.

OVERHEAD TRAVELING CARRIER.

No. 904,119.

Specification of Letters Patent.

Patented Nov. 17, 1908.

Application filed March 24, 1908. Serial No. 423,001.

To all whom it may concern:

Be it known that I, GEORGE HENRY DOWNS, a citizen of the United States, and a resident of North Powder, Union county, State of Oregon, have invented a new and useful Improvement in Overhead Traveling Carriers, of which the following is a specification, reference being had to the accompanying drawings as constituting a part thereof.

10 This invention relates to traveling carrier systems comprising an elevated cable or rail, a carrier traveling thereon, and a weight suspended from the carrier.

15 To comprehend the purpose of my invention, I will briefly describe the utility of the same, with respect to an overhead cable, from which description its utility for other purposes, as for example, an elevated rail, will be self evident.

20 In the case of an overhead cable, it is desirable to use lateral ropes or stays, at intervals along the course of the cable, to prevent the lateral swinging of the latter; but such arrangement would necessitate the lifting of 25 the carrier across said lateral stays, unless the carrier was specially constructed, as in my invention; furthermore, it is desirable that the carrier be so arranged as to prevent it getting off and becoming displaced on the 30 cable while traveling along the same, which occurrence is a most annoying accident.

35 My invention, therefore, has for its primary object to obtain a carrier which is so constructed as to be able to pass over crossing stay-cables, and is furthermore so constructed that the same cannot become displaced on the cable or other track over which it is traveling.

40 To this end my invention comprises the arrangement and combination of parts illustrated in the drawings and hereinafter fully described and claimed.

45 In said drawings, Figure 1 is a perspective side elevation of my improved carrier, representing the same as running on a carrier-cable having lateral stays, and my carrier being seen in the act of crossing one of such lateral stays; Fig. 2 is a side elevation of my carrier with its near side-portion removed, and representing my carrier as traveling on a carrier-cable and in the act of crossing one of its lateral stays; Fig. 3 is a central cross-section of my carrier, representing the same in a similar situation as 50 shown in the preceding figure; and Fig. 4

is a sectional detail on a larger scale, showing a modified construction of my carrier, more fully explained in the body of the specification.

Referring now to the letters as designating the parts described: My carrier comprises two sides pieces *a*, *b*, by which the load is supported, said sides being star-shaped when looked at in side elevation, that is to say, each has a rim portion assembling radially projecting spokes *c*. The interior opposite faces of the spokes *c* are respectively made with recesses *d*', constituting a sort of annular run-way, concentric with the axis of the carrier.

70 The central portions of the sides *a*, *b* are made with registering apertures through which to insert an axle-bolt *e*, secured in place by nuts *f*, fastened on its projecting ends and made with a central boss-portion *g*, 75 on which is journaled a grooved-rim wheel *h*, the latter being arranged intermediate of the sides, as shown in the cross section Fig. 3. Supplementary nuts *f*' are also secured

80 on the extremities of the axle-bolt *e*, and between the nuts *f*, *f*' are secured the members of a yoke *t*, as shown in dotted outline in Fig. 1, to which to fasten the cable (not shown). The boss is so arranged that the sides *a*, *b* may be jammed against the same 85 by the nuts *f* without binding the wheel *h*. Suspended in the annular run-way or recesses *d*, of the sides *a*, *b*, is a hanger *i*, made with lateral shoulders *j*, convexed on their under surface, as more clearly seen in Fig. 2, 90 so as to ride on corresponding shoulder-portions *k*, being wall portions of said recesses *d* of the spoke-like rims *c*. In order to reduce the friction imposed by the shoulders *j* of the hanger *i*, upon the shoulders *k* of 95 said spoke-like rims *c*, it is practical to provide one of the bearing surfaces with ball-bearings.

99 In the construction illustrated by Fig. 3, the ball-bearings *l*, *l*' are seated in the bearing faces of the hanger *i*. Supposing now that *m* represents a length of the carrier-cable, and *n* one of the transverse or lateral stay-ropes, and supposing further that my traveling carrier is in the act of crossing one of such lateral stays, as shown in the drawings, it will be noted that the spoke-like rims *c* of the sides *a*, *b* have straddled the stay-ropes *n*, and therefore, as the carrier continues to move along the cable *m*, 105 110

the sides *a*, *b* will be rotated by reason of the contact of the rim-portion *c* with the stay-rope, thus causing the hanger *i* to pass from one series of recesses *d* in the sides to 5 contiguous recesses thereof, with the result that the hanger will maintain its pendent position. In other words, the hanger merely slides from one series of spoke-like rim portions of the sides to another while passing 10 lateral stays.

In the modified construction shown in Fig. 4, the spokes *c*² of the sides *a'*, *b'* are made with run-ways or recesses *o*, arranged similar to the recesses *d* of the previous example, but provided with flanges *p*, and the hanger *q* is made with corresponding recesses *r*, *r'*, so as to be adapted to ride in said recesses *o*, on said flanges *p*; and the ball-bearings *s*, *s'* are provided in the bearing faces of the spoke-like rim portions *c*², instead of in the bearing faces of the hanger *q*, as in the previous example. The object of the flanges *p* and the corresponding recesses *r*, *r'* is to obtain an interlocking contact between the parts holding the same against separation by reason of any lateral wrenching strain. Obviously, either of the constructions described prevents the wheel *h* from leaving the carrier-cable by reason of 30 any accident. The load is suspended from the hook *u* of the hanger *i*.

I claim:

1. An overhead carrier consisting of a journal-pin, a wheel mounted centrally thereon, sides mounted on said journal-pin exterior of the wheel, the rims of said sides extending beyond the periphery of the wheel and constituting rims therefor, and being divided into a plurality of spoke-like rim-projections, spaced apart, so as to be adapted to straddle a cross wire, said spoke-like rim-projections being provided on opposed faces with a run-way, and a hanger adapted to slide in said run-way of the sides.

2. An overhead carrier consisting of a journal-pin, a wheel mounted centrally thereon, sides mounted on said journal-pin exterior of the wheel, the rims of said sides extending beyond the periphery of the wheel and constituting rims therefor, and being divided into a plurality of spoke-like rim-projections, spaced apart, so as to be adapted to straddle a cross wire, said spoke-like

rim-projections being provided on their interior opposed faces with recesses constituting a run-way, a hanger made with lateral flanges adapted to slide in said run-way of the sides, and ball-bearings interposed between the bearing faces of said lateral flanges of the hanger and the bearing faces of said run-way in the sides.

3. An overhead carrier consisting of a journal-pin, a wheel mounted centrally thereon, sides mounted on said journal-pin exterior of the wheel, the rims of said sides extending beyond the periphery of the wheel and constituting rims therefor, and being divided into a plurality of spoke-like rim-projections, spaced apart, so as to be adapted to straddle a cross wire, said spoke-like rim-projections being provided on their interior opposed faces with recesses constituting a run-way, a hanger made with lateral flanges adapted to slide in said run-way of the sides, and means arranged to prevent the spreading of the sides apart by any undue lateral strain on the hanger, and ball-bearings interposed between the bearing faces of said lateral flanges of the hanger and the bearing faces of said run-way in the sides.

4. An overhead carrier consisting of a journal-pin, a wheel mounted centrally thereon, sides mounted on said journal-pin exterior of the wheel, the rims of said sides extending beyond the periphery of the wheel and constituting rims therefor, and being divided into a plurality of spoke-like rim-projections, spaced apart, so as to be adapted to straddle a cross wire, said spoke-like rim-projections being provided on their interior opposed faces with recesses constituting a run-way, a hanger made with lateral flanges adapted to slide in said run-way of the sides, ball-bearings interposed between the bearing faces of said lateral flanges of the hanger and the bearing faces of said run-way in the sides, and interlocking ribs on the bearing faces of said run-way and the flanges of said hanger, whereby the spreading apart of the sides by undue lateral strain on the hanger is prevented.

GEORGE HENRY DOWNS.
